UNITED STATES PATENT OFFICE

WILLIAM W. MORRAL, OF MORRAL, OHIO

CORN BUTTING MACHINE

Application filed January 28, 1929. Serial No. 335,467.

This invention relates to a corn butting and husking machine.

One object of the invention is to provide such a machine having improved means for feeding the ears to the butt removing device.

A further object of the invention is to provide a double butting and husking machine in which separate butt removing devices will deliver the ears respectively to husking rollers in positions parallel with the length of those rollers.

A further object of the invention is to provide such a machine in which the husking rollers will be provided with devices for turning the ears about their longitudinal axes to bring different portions thereof into contact with the rollers.

Other objects of the invention will appear as the mechanism is described in detail.

In the accompanying drawings Fig. 1 is a plan view of a butt removing mechanism, which may form part of a combined butter and husker; Fig. 2 is a side elevation of such a butt removing mechanism; Fig. 3 is a plan view of a similar butt removing mechanism having modified feeding mechanism; Fig. 4 is an end elevation of the machine of Fig. 3; Fig. 5 is a side elevation of the machine of Fig. 3, with the conveyor and chute in section; Fig. 6 is a section taken on the line 6-6 of Fig. 3; Fig. 7 is a view similar to Fig. 6 showing a further modification of the feeding mechanism; Fig. 8 is a plan view of a double corn butting and husking machine; Fig. 9 is a section taken on the line 9-9 of Fig. 8; Fig. 10 is a section taken on the line 10-10 of Fig. 9, showing the ear turning device; Fig. 11 is a plan view of portions of one pair of husking rollers showing a modified form of ear turning device; Fig. 12 is a section taken transversely of Fig. 11; and Fig. 13 is a plan view of a modified form of double corn butter and husker.

In these drawings I have illustrated several embodiments of my invention but it will be understood that these embodiments have been chosen for the purposes of illustration only and the mechanism may take various forms and may be assembled in various ways

without departing from the spirit of the invention.

In Figs. 1 and 2 I have shown a butt removing mechanism which may, if desired, form part of a combined butt removing and husking mechanism. As there shown, the machine comprises a main frame 1 having mounted near one end thereof a butt removing device which, in the present instance, comprises a pair of overlapping blades or disks 2 and 3 rotatably mounted on parallel shafts 4 and 5. Extending lengthwise of the machine and in advance of the butt removing device is a gaging device which, in the form here shown, comprises upper and lower spiral rollers 6 and 7 spaced apart to receive between them the butt end of an ear of corn and to properly position that ear with relation to the butt removing device and advance the butt toward the butt removing device as the body of the ear is advanced by the feeding mechanism.

The feeding mechanism comprises upper and lower feeding devices, the lower feeding device being here shown as comprising a rotatable drum 8 mounted on a fixed axis and having a series of longitudinally extending peripheral grooves 9. The upper feeding device comprises in part a similar drum 10 having a circumferential series of longitudinally extending peripheral grooves 11. The peripheral grooves of the two drums are arranged to be brought into line as the drums rotate and to receive between them ears of corn and feed these ears to the butt removing device. A feeding mechanism comprising similar drums is shown and described but not claimed in the application filed by me May 16, 1928, Serial No. 278,212. Preferably the upper drum 10 is movable toward and from the lower drum and to this end I have shown the same as carried by a shaft 12 which is journaled in an elongated bearing 13 carried by an arm 14 journaled on the shaft 4 of the upper butt removing blade or disk 2. The upper feeding device further comprises a short spiral roller 15 arranged in advance of the drums 8 and 10 and above the discharge end of a conveyor 16. This conveyor is here shown as an endless belt or chain the upper

stretch of which travels through a trough-like chute 17, the forward side of which is cut away, as shown at 18, to permit the ear to be moved laterally from the conveyor. The spiral feeding roller 15 is preferably yieldably mounted so that it may accommodate itself to ears of different sizes and is here shown as carried by an arm 34 pivotally mounted on the shaft of the upper gaging roller 6. If desired, the weight of the roller may be counterbalanced or partially counterbalanced by a spring 35 which is connected with an arm 36 extending upwardly from the arm 34.

Arranged between the gaging rollers 6 and the feeding mechanism is a husk loosening device which preferably consists of a pair of resilient arms 19 which, adjacent to the conveyor 16, are spaced one from the other far enough to permit the passage of an ear of corn between them and which converge forwardly and have their forward portions provided with prongs or teeth 20 to engage the husks of an ear of corn and loosen the same as the ear is advanced by the feeding mechanism.

In operation the ears of corn are deposited one at a time on the conveyor 6 with the butt ends foremost and are carried by the conveyor beneath the short spiral roller 15 which cooperates with the conveyor to move the butt end of the ear into engagement with the gaging rollers and which also serves to move the ear transversely to its length off the conveyor and into engagement with the feeding drums 8 and 10. The lower member of the husk loosening device will prevent the rear end of the ear from dropping as it leaves the conveyor but even in the absence of this husk loosening device the end of the ear would drop into contact with the lower feeding drum 8 which would immediately lift the same to its proper position. The two drums then engage the ear and move it forwardly into contact with the butt removing device, or cutters 2 and 3, which sever the butt therefrom. The ear may be discharged from the butt removing device in any desired manner but preferably is discharged directly to the husking rollers as will hereinafter appear.

In Figs. 3 to 6 I have illustrated a butt removing mechanism which in most respects is similar to that shown in Figs. 1 and 2 but which employs a slightly different form of feeding mechanism. Mounted on the supporting frame 21 is a butt removing device which, in the present instance, comprises a single rotary blade 22 carried by a shaft 23 and cooperating with the cutter bar 24. Arranged in advance of this butt removing device are gaging rollers 25 which position the ear with relation to the butt removing device and advance the butt toward that device. A husk loosening device 26 similar to that above described is arranged alongside the gaging

rollers between the same and the feeding mechanism. The feeding mechanism comprises upper and lower rotatable members, the upper feeding member being in the form of a spiral roller 27 and the lower feeding device being in the form of a spiral roller 28 of a length considerably less than the length of the upper feeding roller 27. A conveyor 29 operating in a trough or chute 30, as above described, has its discharge end arranged in advance of the lower feeding roller and beneath the rear end of the upper feeding roller so that ears of corn will be delivered by the conveyor beneath the upper feeding roller which will cooperate with the conveyor to move the ear toward the gaging rollers and will simultaneously advance the ear so as to move the same off of the conveyor and into engagement with the lower feeding roller 28. The two feeding rollers will then cooperate to move the ear to and past the butt removing device.

Preferably the upper feeding roller 27 is movable toward and from the lower feeding roller. As here shown, this roller is carried by arms 31 and 32 which are pivotally mounted on or adjacent to the axis of the upper gaging roller. In this manner the upper feeding roller is permitted to rise and fall so as to accommodate itself to ears of different sizes and it may, if desired, be counterbalanced or partly counterbalanced by springs 33.

In Fig. 7 I have shown a slight modification of the feeding mechanism shown in Figs. 3 to 6. As there shown, the butt removing device comprises two blades or rotary disks 37 and a pair of spiral gaging rollers 38 arranged in the manner above described. The feeding mechanism comprises two lower spiral rollers 39, arranged in the same horizontal plane, and in place of an upper roller I have provided a movable plate or shoe 40 which is yieldably supported above the rollers 39 by an arm or arms 41, which arm is acted upon by a spring 42 to press the shoe into contact with an ear resting on the lower feeding rollers. The shoe is of a length substantially equal to the length of the feeding rollers and the ear is delivered thereto by a conveyor 43. In this form of device the two lower feeding rollers hold the ear against tilting movement and the yieldable shoe 40 presses the same into contact with the spiral rollers so that it will be advanced thereby.

In Figs. 8 and 10 I have illustrated a double butting and husking machine which embodies within itself two complete butting and husking mechanisms operating from a common source of power and through driving mechanism which in part is common to both devices. The arrangement is simple and has the advantage of compactness as it will occupy much less floor space than would two

separate machines capable of performing the same amount of work. The several parts of this double machine are mounted on a single frame 44. Near the center of the frame is 5 mounted two pairs of inclined husking rollers 45 and 46. Preferably one roller of each pair, in the present instance the roller 45, is arranged on a slightly lower level than the other roller, as is more clearly shown in 10 Fig. 10. The husking rollers may be of any suitable character but I have here shown them as provided with a circumferential series of longitudinal ribs 47, the ribs on the two rollers intermeshing after the manner 15 of spur gears.

The butt removing mechanisms extend transversely to the respective pairs of husking rollers and each butt removing mechanism comprises a butt removing device, preferably a pair of rotatable disks 48, and spiral gaging rollers 49 to position the ears with relation to the butt removing devices. The feeding mechanism is similar to that shown in Figs. 1 and 2 and comprises a lower 20 grooved drum 50, mounted on a fixed axis, and an upper grooved drum 51 mounted on a movable axis. The upper feeding device also comprises a short spiral roller 52 beneath which extends the conveyor 53. The butting operation 25 is the same as that described in connection with the device of Figs. 1 and 2 and the butted ears are delivered from the butt removing mechanism to the respective pairs of husking rollers by inclined chutes 54, the arrangement being such that the ears will move transversely to their length from the butt removing device to the husking rollers and will be delivered to the husking rollers in positions parallel with the axes thereof 30 and will travel downwardly along the husking rollers, the latter being in the present instance inclined so that the ears will travel down the same by gravity.

If desired, the husking rollers may be provided with means for turning the ears about their longitudinal axes as they travel along the husking rollers, so as to present different portions of the same to the rollers. As shown in Figs. 9 and 10 the lower roller 45 of each pair of husking rollers is provided with circumferential grooves 55 in each of which is mounted a turning device or agitator plate 56. As here shown, the plate 56 has a longitudinal slot 57 to receive the reduced portion of the roller, the roller being preferably made in sections and the agitator plates mounted thereon when the several sections are assembled. The turning device or plate 56 is of such a character that when 40 in its lowermost position the upper edge thereof will lie below the surface of the husking roller 45 but when the plate is elevated this upper edge will project above the roller and engage the adjacent side of an ear which rests in contact with the two husking rollers,

thus causing that ear to be turned about its longitudinal axis. Movement may be imparted to the turning device or plate 56 in any suitable manner but I prefer to utilize a cam for this purpose and to this end each plate has in its lower portion an opening 58 through which extends a shaft 59. Rigidly secured to this shaft and arranged within the respective openings 58 are eccentric disks or cams 60 so arranged that as the shaft 70 rotates the cams will engage the upper edges of the respective openings and elevate the plate. Springs 61 serve to move the turning devices to their lowermost positions and to hold the same in contact with the cams 60. 80

In Figs. 11 and 12 I have shown a different form of ear turning device. As there shown, both the upper roller 62 and the lower roller 63 are provided with circumferential grooves 64 and 65, respectively. Rigidly secured to the lower roller, in the groove 65, is an eccentric disk 66 which projects beyond one side only of the roller 63 and which is adapted to enter the groove 64 of the roller 62 as the rollers rotate. It will be apparent 90 that once during each rotation of the roller 63 this eccentric disk will engage an ear resting upon the two rollers and impart a turning movement thereto.

In Fig. 13 there is shown a modified form 95 of a double butting and husking machine in which the ear travels parallel with the husking rollers during the butting operation. In this machine the husking mechanism comprises two pairs of husking rollers 67 and 68 arranged substantially as described in connection with Figs. 8 to 10. Arranged on each side of the husking rollers is a butting mechanism which as here shown comprises a rotatable blade 69 mounted on a shaft 70 extending 100 transversely to the husking rollers, the blades 69 of the two butt removing devices being mounted on the same shaft. Arranged in advance of the butt removing device and extending lengthwise of the husking rollers is a pair 105 of spiral gaging rollers 71. The gaging rollers of the two butt removing devices being driven from a common shaft 76. Arranged parallel with the gaging rollers is the feeding mechanism which comprises two lower feeding rollers 72 and 73 arranged in substantially the same horizontal plane, and a single upper feeding roller 74 arranged above and in a vertical plane between the axes of the two lower feeding rollers. The ears are delivered to the feeding mechanism by a conveyor 76 similar to that above described and the lower feeding roller 72 is cut away or shortened to permit the discharge end of the conveyor to extend beneath the upper feeding roller 74. As the ears are carried past the butt removing device, by the feeding rollers, they are discharged into inclined chutes 75 down which they move by gravity to the respective pairs of husking rollers 67 and 68. 110

While I have shown and described certain embodiments of my invention I wish it to be understood that I do not desire to be limited to the details thereof as various modifications may occur to a person skilled in the art.

Having now fully described my invention, what I claim as new and desire to secure by Letters Patent, is:

1. In a mechanism of the character described, a butt removing device, a gaging device to position an ear of corn with relation to said butt removing device, a feeding member extending lengthwise of said gaging device, means to guide an ear of corn into engagement with said gaging device and comprising a part extending across said feeding member to support said ear of corn in engagement therewith, and another feeding member arranged between said guiding means and said butt removing device to engage said ear of corn when the latter has been moved laterally with relation to said guiding means by the first mentioned feeding member.
2. In a mechanism of the character described, a butt removing device, a gaging device to position an ear of corn with relation to said butt removing device, a spiral feeding member extending lengthwise of said gaging device, means for delivering an ear of corn to said gaging device and comprising a conveyor having a part extending beneath said spiral roller, and a feeding member arranged between said conveyor and said butt removing device to engage the ear of corn when it has been moved transversely with relation to said conveyor by said spiral feeding member.
3. In a mechanism of the character described, a butt removing device, a gaging device to position an ear of corn with relation to said butt removing device, means to guide an ear of corn into engagement with said gaging device, and a mechanism to feed said ear of corn to said butt removing device and comprising an upper spiral roller arranged above the inner end portion of said guiding means, and a lower rotatable grooved feeding member arranged between said guiding means and said butt removing device to receive said ear of corn from said guiding means after it has been moved into engagement with said gaging device.

4. In a machine of the character described, a butt removing device, a gaging device to position an ear of corn with relation to said butt removing device, a feeding mechanism to move said ear of corn toward and past said butt removing device and comprising upper feeding means and lower feeding means, said upper feeding means having a part extending rearwardly beyond the lower feeding means, and a conveyor arranged transversely to said feeding mechanism and having one end extending beneath the rearwardly extending part of said upper feeding means.

5. In a machine of the character described,

a butt removing device, a gaging device to position an ear of corn with relation to said butt removing device, a feeding mechanism to move said ear of corn toward and past said butt removing device and comprising upper feeding means and lower feeding means, said upper feeding means comprising a spiral roller extending rearwardly beyond said lower feeding means, and a conveyor arranged transversely to said feeding mechanism and having its discharge end arranged beneath said spiral roller, whereby said roller will operate therewith in moving the ear into engagement with said gaging device and will move said ear transversely of its length into engagement with said lower feeding means.

6. In a machine of the character described, a butt removing device, a gaging device to position an ear of corn with relation to said butt removing device, a feeding mechanism to move said ear of corn toward and past said butt removing device and comprising upper feeding means and lower feeding means, said upper feeding means having a part extending rearwardly beyond the lower feeding means, and a device for delivering ears of corn to said feeding mechanism comprising a trough extending transversely to said feeding mechanism and having its front wall spaced from said upper feeding means, and a conveyor extending through said trough and beneath the rearwardly extending portion of said upper feeding means.

7. In a machine of the character described, a butt removing device, a gaging device to position an ear of corn with relation to said butt removing device, feeding rollers rotatable about axes transverse to said gaging device, and each having a series of peripheral grooves extending axially thereof, said feeding rollers being arranged to receive an ear of corn between them in corresponding grooves and move said ear toward said butt removing device, and means arranged in advance of said feeding rollers to move an ear of corn into engagement with said gaging device and to then deliver said ear of corn to said feeding rollers.

8. In a machine of the character described, a butt removing device, a gaging device to position an ear of corn with relation to said butt removing device, feeding rollers rotatable about axes transverse to said gaging device and each having a series of peripheral grooves extending axially thereof, said feeding rollers being arranged to receive an ear of corn between them and move said ear toward said butt removing device, means for guiding an ear of corn into engagement with said gaging device, and means for moving said ear of corn into engagement with said feeding rollers.

9. In a machine of the character described, a butt removing device, a gaging device to position an ear of corn with relation to said

- butt removing device and having means to advance the butt end of said ear toward said butt removing device, a conveyor to deliver an ear of corn to said gaging device, a feeding mechanism comprising upper and lower grooved feeding members arranged between said conveyor and said butt removing device to receive said ear of corn between them and to move the same into engagement with said butt removing device, and a device arranged above the discharge end of said conveyor to move said ear of corn transversely to its length from said conveyor into engagement with said feeding members.
- 10 15. In a machine of the character described, a butt removing device, a gaging device to position an ear of corn with relation to said butt removing device and having means to advance the butt end of said ear toward said butt removing device, a conveyor to deliver an ear of corn in the direction of its length to said gaging device, a pair of feeding drums arranged between said conveyor and said butt removing device on axes transverse to said gaging device and each having a series of peripheral grooves extending axially thereof, and a spiral roller extending above the discharge end of said conveyor to move an ear of corn transversely to its length from said conveyor into engagement with said grooved feeding drums.
- 20 25 30 35 40 45 50 55 60 65 70 75 80 85 90 95 100 105 110 115 120 125 130
11. In a machine of the character described, a butt removing device, a gaging device to position an ear of corn with relation to said butt removing device and having means to advance the butt end of said ear toward said butt removing device, a conveyor to deliver an ear of corn in the direction of its length to said gaging device, a feeding mechanism comprising upper and lower grooved feeding members arranged between said conveyor and said butt removing device to receive said ear of corn between them and to move the same into engagement with said butt removing device, a device arranged above the discharge end of said conveyor to move said ear of corn transversely to its length from said conveyor into engagement with said feeding members.
12. In a machine of the character described, a butt removing device, a gaging device to receive the butt end of an ear of corn and position the same with relation to said butt removing device, cooperating feeding wheels mounted for rotation about axes extending transversely to said gaging device and arranged to receive an ear of corn between them and move said ear toward said butt removing device, and means arranged in advance of said feeding wheels for moving an ear of corn into engagement with said gaging device and for then moving said ear transversely to its length to said feeding wheels.
13. In a machine of the character described, a butt removing device, a gaging device to position an ear of corn with relation to said butt removing device, cooperating feeding members mounted for rotation about axes extending transversely to said gaging device and arranged to receive an ear of corn between them and move said ear toward said butt removing device, means for guiding an ear of corn in the direction of its length into engagement with said gaging device, and means for moving said ear of corn transversely to its length from said guiding means into engagement with said feeding members.
14. In a machine of the character described, a butt removing device, a gaging device to position an ear of corn with relation to said butt removing device, and having means to advance the butt end of said ear toward said butt removing device, a conveyor to deliver an ear of corn in the direction of its length to said gaging device, feeding mechanism comprising upper and lower feeding members mounted between said conveyor and said butt removing device for rotation about axes extending transversely to said gaging device, and arranged to receive an ear of corn between them and move the same toward said butt removing device, and a device arranged above the discharge end of said conveyor to move said ear of corn transversely to its length from said conveyor into engagement with said feeding members.
15. In a machine of the character described, a butt removing device, a gaging device to position an ear of corn with relation to said butt removing device, and having means to advance the butt end of said ear toward said butt removing device, a conveyor to deliver an ear of corn in the direction of its length to said gaging device, feeding mechanism comprising upper and lower feeding members mounted between said conveyor and said butt removing device for rotation about axes extending transversely to said gaging device and arranged to receive an ear of corn between them and move the same toward said butt removing device, and a spiral roller extending above the discharge end of said conveyor to move an ear of corn transversely to its length from said conveyor into engagement with said feeding members.

ear toward said butt removing device, a conveyor to deliver an ear of corn in the direction of its length to said gaging device, feeding mechanism comprising upper and lower feeding members mounted between said conveyor and said butt removing device for rotation about axes extending transversely to said gaging device, and arranged to receive an ear of corn between them and move the same toward said butt removing device, a device arranged above the discharge end of said conveyor to move said ear of corn transversely to its length from said conveyor into engagement with said feeding members, and a pair of husk loosening members arranged between said gaging device and said feeding mechanism and having those portions thereof which are adjacent to said conveyor spaced apart to permit the ear of corn to pass between them into engagement with said gaging device.

In testimony whereof, I affix my signature hereto.

WILLIAM W. MORRAL.
